(57) **CLAIM**

The ornamental design for a bike rack, as shown and described.

DESCRIPTION

FIG. 1 is a front, left and top perspective view of a bike rack, showing my design.

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof; and,

FIG. 8 is an enlarged view of portion 8 shown in FIG. 1. The broken lines in the drawings illustrate the portions of the bike rack, which form no part of the claimed design. In addition, the dot-dash broken lines in the drawings illustrate an enlarged portion of the design.

1 Claim, 8 Drawing Sheets
